UNITED STATES PATENT OFFICE.

JOSEPH D. WESTGATE, OF WORCESTER, MASSACHUSETTS, ASSIGNOR, BY
MESNE ASSIGNMENTS, TO THE ECCENTRIC PULLEY AND STOP-MOTION
COMPANY, OF PORTLAND, MAINE.

CLUTCH.

SPECIFICATION forming part of Letters Patent No. 412,296, dated December 9, 1890.

Application filed February 15, 1889. Serial No. 299,995. (No model.)

To all whom it may concern:

Be it known that I, JOSEPH D. WESTGATE, of Worcester, in the county of Worcester and State of Massachusetts, and a citizen of the United States, have invented a new and useful Improvement in Clutches, of which the following is a specification containing a full, clear, and exact description of the same, accompanied by drawings, in which—

Figure 1 denotes a central sectional view. Fig. 2 is a view of the side of the actuating-eccentric, the shaft being shown in section on line X X, Fig. 1. Fig. 2 also shows a portion of the removable cover C; and Fig. 3 is a view of the side of the collar attached to the shaft and the inclosing friction-strap, the shaft being shown in section on line X X, Fig. 1. Fig. 4 is a view of the friction-clutch with a portion of the shaft to which it is applied, and Fig. 5 is a side view of the same.

Similar letters refer to similar parts in the several views.

A denotes the shaft to which the collar A' is attached.

B is a belt-pulley capable of rotating about the shaft A, and provided with a web B' on one side of the pulley and a removable cover C, attached to the pulley by means of screws a. B² is a hub of the pulley, which forms the bearing upon the shaft A.

D is a solid friction-ring inclosing the collar A', and having on one side a projecting lug b entering an opening c in the web B' of the pulley, by means of which the friction strap or ring D is made to rotate with the pulley B around the shaft A. Upon the opposite side of the friction-ring D is a roll D', which turns on a stud D² held in the ring D.

E is an eccentric turning on the shaft A and having a flange e and a hub f, provided with a flange g, forming a neck h.

F is a sliding collar provided with a groove j, extending partially around the collar to receive a shipper consisting of a curved prong j' and a lever-handle. (Represented in broken lines at j'.) The ends of the curved prong rest against the shoulders j³ j³, and thereby prevent the collar from turning on the shaft A. The collar F has a flange k overlapping the

hub of the eccentric E and engaging the neck h, so that a sliding motion of the collar F along the shaft A will impart a corresponding sliding movement to the eccentric E and at the same time allow the eccentric to turn freely on the shaft A and within the flange k of the collar F.

The purpose of the above-described device is to move the eccentric along the shaft, and I accomplish this purpose by means of the collar F, with its flange k overlapping the flanged hub of the eccentric, as described; but I do not confine myself to the construction shown. Neither does the specific device shown and described form any portion of my present invention.

The flange e of the eccentric has a spur e' projecting radially from the edge of the flange e and resting in a recess e² in the cover C. A projecting rib m on the cover C rests against the spur e', causing the eccentric E to rotate with the pulley B as the latter is rotated around the shaft A by means of power applied to its face, and thereby maintaining the thin side E' of the eccentric opposite the roll D', so that as the collar F is moved along the shaft by means of the shipper-rod (indicated by broken lines in Figs. 4 and 5) the collar will cause the eccentric to slide along upon the shaft, and the thin side E' of the eccentric will be carried under and beneath the roll D. The collar F, being held from rotation by the shipper, will allow the disk C and connected pulley to rotate by means of the opening j⁴ in the disk, as represented in Fig. 5.

The edge of the eccentric is slightly chamfered at n to allow the eccentric to be readily pushed beneath the roll, which crowds the eccentric upon the shaft A, causing the friction between the eccentric and shaft to be greater than that between the eccentric and the roll D', allowing the roll to run around the eccentric as the eccentric becomes attached to the shaft by means of the friction between it and the shaft. As the pressure increases between the eccentric and the roll D', the eccentric becomes held more firmly upon the shaft, and the motion of the roll around the eccentric increases the pressure

against the roll D' and draws the opposite side of the friction-ring D firmly against the side A² of the collar A', producing a friction between the collar and the inner surface of the friction-ring and tending to cause the rotary motion of the pulley B to be imparted through the ring D and the collar A' to the shaft A. In case the friction between the collar A' and the friction-ring D is not sufficient to cause the rotary motion of the pulley B to be imparted to the shaft A, the sliding motion of the collar F and eccentric E is continued, carrying the eccentric nearer to the fixed collar A' until the tooth or spur p on the side of the eccentric E is made to enter one of the radial grooves or recesses r in the opposing side of the fixed collar A', causing the eccentric to be rigidly held upon the shaft A and the rotary motion of the pulley to be positively imparted to the shaft A through the roll D' and eccentric E.

In the position of the eccentric E, as illustrated in Fig. 1 of the drawings, the radial spur e' is shown as resting against the rib m upon the cover C, causing the eccentric to be rotated around the shaft A as the pulley is rotated; but as the eccentric is moved along the shaft A by the shipper-lever engaging the collar F the radial spur e' is carried past the rib m, and the pulley B and attached cover C revolve around the shaft A independently of the eccentric, which becomes attached to the shaft A by the pressure of the eccentric E against the roll D', as already described. When the eccentric is again moved away from the fixed collar A' and from beneath the roll D', the radial spur e' is again brought into the recess e² of the cover, and the rotation of the cover around the shaft will cause the eccentric to be carried with it by the contact of the rib m with the radial spur e'.

What I claim as my invention, and desire to secure by Letters Patent, is—

1. In a clutch, the combination, with a shaft and a friction-collar attached to said shaft and a pulley revolving around said collar and shaft, of a friction-ring inclosing said fixed collar and carried by the rotation of said pulley around said collar, a roll projecting on one side, and a sliding eccentric moving on said shaft, whereby it is carried beneath the roll on said friction-ring and the inner surface of said ring pressed against the outer surface of said friction-collar, substantially as described.

2. In a clutch, the combination, with clutching devices, substantially as described, whereby the rotation of a pulley is imparted to a shaft, or vice versa, of an actuating-eccentric turning loosely on said shaft and capable of

sliding thereon, said eccentric being held from rotation with said shaft when in engagement with said clutching devices by means of its friction upon said shaft, and intermediate mechanism, substantially as described, by which said eccentric is operatively connected with said clutching devices, substantially as described.

3. In a clutch, the combination, with clutching devices, substantially as described, whereby the rotation of a pulley is imparted to a shaft, or vice versa, of an eccentric whereby said clutching devices are actuated, a sliding collar engaging said eccentric and adapted to be moved along said shaft by the shipper, and intermediate mechanism, substantially as described, by which said eccentric is operatively connected with said clutching devices, substantially as described.

4. In a clutch, the combination, with clutching devices whereby the rotation of a pulley is imparted to a shaft, or vice versa, of an eccentric sliding on said shaft, whereby said clutching devices are actuated, said eccentric being provided with a projecting spur, and said pulley having a rib or spur adapted to engage said spur on the eccentric, so that the eccentric is carried around the shaft with the pulley and held relatively in the same position to the clutching devices, substantially as described.

5. In a clutch, the combination, with the shaft and a pulley revolving around said shaft, and a fixed friction-collar attached to said shaft, of a friction-ring inclosing said friction-collar and having a lug entering an opening in said pulley, whereby said friction-collar is carried around with said pulley, said lug adapted to have a slight radial motion in said opening, substantially as described, and connected actuating devices, substantially as described, whereby said friction-ring is pressed against said friction-collar.

6. The combination, with a shaft and a pulley having a rotary motion around said shaft, of the friction-collar A', provided with radial grooves or notches, a friction-ring inclosing said friction-collar and carried around it by the rotation of the pulley, and provided with a roll D', and an eccentric sliding on the shaft and having a spur adapted to engage one of said radial grooves or notches in the friction-collar whenever said eccentric is moved beneath the roll D', and the friction-ring thereby pressed upon said friction-collar, substantially as described.

JOSEPH D. WESTGATE.
